L. L. WILSON

LOOSE JOINT DRILL COLLAR

Filed March 9, 1926

Patented Dec. 7, 1926.

1,609,851

UNITED STATES PATENT OFFICE.

LEONARD LUTHER WILSON, OF TONKAWA, OKLAHOMA.

LOOSE-JOINT DRILL COLLAR.

Application filed March 9, 1926. Serial No. 93,459.

The present invention relates to a loose joint drill collar for use in rotary drills. The ordinary cable drilling tools include a heavy bit suspended on a steel cable which is lifted up and down repeatedly until the hole is drilled to the desired depth. The ordinary rotary drill includes a heavy steel bit suspended from steel drilling pipes, all of which is rotated until the hole is drilled to the desired depth. I propose to provide an exceedingly compact and convenient device whereby it is possible to combine the driving power of the cable tool and the revolving character of the rotary tool.

I further contemplate the provision of a device of this nature which is simple in its construction, easy to assemble and disassemble, strong, durable, efficient and reliable in operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a longitudinal section through a drilling apparatus embodying the features of my invention,

Figure 1^a is a continuation of Figure 1, and

Figure 2 is a transverse cross section taken substantially on the line 2-2 of Figure 1^a.

Referring to the drawing in detail it will be seen that the numeral 5 designates the hollow rod which aids in imparting rotary motion to the bit, not shown, in the usual well known manner. The rod is hollow for the purpose of feeding water to the bit so as to form mud immediately ahead of the bit. This rod 5 is rotatable through the usual shell sections 6 and 7. The shell indicated generally by the letter A has its upper portion 8 threadedly engaged with the section 7 as at 9, and is provided with the oil chamber 10. The rod 5 extends through this oil chamber and has washers disposed thereover in the chamber; springs 13 are disposed about the rod 5 within the chamber 10 between the washers 12. The intermediate portion 14 of the shell A is provided with a hexagonal bore for slidably receiving a hexagonal rod section 15 which is threadedly engaged with the lower end of rod 5. This

rod section 15 is also hollow so that the water may pass therethrough. The lower end of the shell A is indicated by the numeral 17, and receives the head 18 formed on the lower end of the rod section 15. Suitable packing and stop means 19 are disposed in the end 17 for limiting the movement of the head 18 as is quite apparent from the drawing.

An extension 20 is slidable through the stuffing box 19 and a joint 21 of well known formation is attached thereto for engagement with the bit (not shown) in the well known manner.

From the above description it will be seen that the rod 5 will rotate with the shell but is capable of sliding movement in relation thereto. Rotary motion is imparted to the rod 5 in the usual well known manner, and the weight of the shell causes the compression of springs 13 as is quite apparent, thereby giving the desirable driving power to the bit.

I consider that this loose joint drill collar is an improvement over the simple rotary drill which is in itself an improvement upon the cable tools. The improvement consists first in drilling and second in fishing.

Often when a hole has been started, the bit must be hauled up and removed, and a fresh bit put in operation. The new bit seldom, if ever, is of the same precise measurement as the one just removed. If the bit is slightly larger and is dropped down in the hole, the driller has a bit jammed or stuck in the hole and with from fifty to three thousand feet of pipe from which it is suspended and requires several days, oftentimes, to loosen the bit in the hole, whereas with my improvement including the spring arrangement it will permit a play of nearly three feet, which will make the loosening of the bit much easier and more rapid.

When a tool is lost in a hole, it is seldom, if ever, left standing in a perpendicular position, but is much more likely to be left slightly tipped. With the simple rotary tool, there is anywhere from fifty to three thousand feet of drill pipe with the appropriate weight dropped down to the tool, so that the chances are greater that the lost tool may be driven further out of a perpendicular position so that the fishing tool will not slip over the top of the lost tool and grab it. In the present device, however, the

tool can be lowered simply to contact, or a little further than actual contact, and then there will be just enough vibration from the spring to force the fishing tool over the lost tool and yet not enough force to drive the lost tool still further from the perpendicular.

It is thought that the construction, operation, and advantages of this invention will 10 be clearly understood by those skilled in this art without a more detailed description thereof.

The present embodiment of the invention has been disclosed in detail merely by way 15 of example since in actual practice it has attained the features of advantage enumerated as desirable in the statement of the invention and the above description.

It is apparent that numerous changes in 20 the details of construction, and in the combination and arrangement of parts may be resorted to without departing from the spirit or scope of the invention as herein-after claimed or sacrificing any of its advantages.

Having thus described the invention, what

I claim as new and desire to secure by Letters Patent is:—

In a well drill, a plurality of shell sections, a special shell section attached to one 30 of the first shell sections and forming a hull, said hull including an upper portion having a bore, an intermediate portion having a non-circular bore, and a lower end having a bore, rod sections removable through the 35 shell sections, one of said rod sections being disposed in the non-circular bore and being non-circular in conformity therewith to prevent rotation independently of the special shell section, a spring structure including 40 washers disposed about the other rod section in the upper end of the special shell section, and springs disposed between the washers so that said spring structure impinges against one of the first mentioned 45 shell sections at its upper end, and against the non-circular rod section, at its lower end, for supporting the shell sections on the rod sections.

In testimony whereof I affix my signature.

LEONARD LUTHER WILSON.
